UNITED STATES PATENT OFFICE

EDWARD W. STEVENS AND DONALD A. YOUNG, OF DETROIT, MICHIGAN, ASSIGNEES TO
CHICAGO PNEUMATIC TOOL COMPANY, OF NEW YORK, N. Y., A CORPORATION OF
NEW JERSEY

SUPPORT FOR POWER TOOLS

Application filed June 6, 1928. Serial No. 283,438.

This invention relates to supports for power tools, particularly of the pedestal or column type.

One object of the invention is to provide a compact structure of the described type having improved features of adaptability and adjustability. Another object is to enclose and protect the control mechanism. Another object is to provide for convenient diversion of the exhaust for a fluid pressure tool away from the operator. Other objects will be apparent from the detailed description which follows.

In order to illustrate the invention, one concrete embodiment thereof is shown in the accompanying drawing in which:

Fig. 1 is a side elevational view showing portions of the power tool and control device therefor in section;

Fig. 2 is a detailed view on a greatly enlarged scale showing the upper end of the pedestal support and the power tool control device in section; and

Fig. 3 is a detailed sectional view substantially on the line 3—3 of Fig. 1.

The embodiment of the invention chosen for the purpose of illustration comprises a support in the form of a pedestal having a base A formed with a hollow upright portion in which is adjustably supported a hollow post B, preferably cylindrical in form, which is held in adjusted position by clamping bolts 4 which extend through flanges in the slotted upper end of base A. Supported upon post B for axial and radial adjustment are arms C and D, which may be of any suitable shape and extent, the inner ends of which are formed as slotted collars encircling post B and provided with flanges through which extend clamping bolts similar to those used on base A and indicated by the same reference character 4. In accordance with the usual practice one of the arms, such as C, is arranged to support the work while the other arm D carries a power tool of any suitable or desired type. Inasmuch as the apparatus herein shown is to be used for riveting, arm C supports an anvil set c while arm D supports a complete percussive motor of the fluid pressure type.

The motor itself, indicated at 5, is slidably mounted in a casing 6, the motive fluid admitted to actuate the motor being operable to move the same toward the work and a spring 7 being utilized to withdraw the motor. The space between motor 5 and casing 6, in which spring 7 is housed, is utilized for the exhaust of the motor and means associated with the securing of the power tool to its supporting arm D are utilized for directing the exhaust away from the operator. To this end the outer portion of arm D is formed as an elongated tang d which extends into a slot provided by spaced flanges 8 on tool casing 6 (Fig. 3), bolts 9 extending through bores in flanges 8 and tang d to hold the power tool on its supporting arm. As clearly shown in Fig. 3 and indicated by dotted outline in Fig. 1, tang d does not extend to the bottom of the slot between flanges 8 of the tool casing but leaves a space 10 which is utilized as an exhaust passage, ports 11 being provided in casing 6 to permit the exhaust motive fluid within the casing to reach passage 10 which directs the same axially of the power tool.

The motive fluid supply to the power tool 5 is provided by a line 12 which includes a control device, or throttle valve, 13, which is supported by one or more brackets 14 on arm D above and in axial alignment with post B. Since the control device 13 may be of any suitable or desired type and, as shown, is wholly conventional, description thereof is omitted. The means for actuating the control device forms an important feature of the invention, the arrangement being such that the parts are protected against injury and are conveniently arranged for adjustment. In the form shown an operating lever 15 is pivotally mounted in base A and is provided with a projecting pedal or treadle 15a for actuation by the foot of the operator. Extensible and contractable linkage is provided in the hollow bore of post B and in the pedestal portion of base A. The linkage or connection comprises telescoping rods 16 and 17, the former being hollow to receive the latter, which is provided with screw threads throughout the greater portion of its length.

Hollow rod 16 has, at its upper end and in threaded engagement with its exterior, a nut 18 the upper portion of which has a restricted threaded bore which is in threaded engagement with rod 17. Between the top of post B and control device 13 into which rod 17 extends, the rod is provided with a knurled portion 17a to permit rod 17 to be conveniently rotated to screw it through nut 18 and into or out of telescoping relation with hollow rod 16. The lower end of rod 16 has secured thereto a clevis 19 which connects the rod to operating lever 15 and prevents hollow rod 16 from turning. A coil spring 20 encircling the lower end of rod 16 between clevis 19 and a perforated stop plate 21 in the lower portion of the pedestal of base A yieldingly maintains rod 16 in its lowermost position and the pedal portion of lever 15 in its uppermost position. The portion of rod 17, which extends into control device 13, has an elongate slot 17b which receives a cotter pin 22 to lock rod 17 in adjusted position. In order to adjust the length of the actuating connection for control device 13, the operator withdraws cotter pin 22, grasps the knurled portion 17a and turns it to increase or decrease the length of the telescoping connection 16, 17 and then replace cotter pin 22 after the adjustment is completed.

From the above, it will be apparent that the present invention provides a support of compact and attractive design, which provides for a wide range of adjustment to adapt the same to widely varying requirements, that the actuating mechanism for the control of the power tool is both conveniently adjustable and also fully protected against injury, and that the attachment of the power tool to the supporting arm is such as to dispose of the exhaust of a fluid pressure tool in such a way as to relieve the operator of all discomfort and annoyance.

While a preferred form of the invention has been herein shown and described, it is to be understood that the invention is not limited to the specific details thereof, but covers all changes, modifications and adaptations within the scope of the appended claims.

We claim as our invention:

1. The combination with a fluid pressure tool of a rigid support therefor, and means securing said tool to said support and providing a tang and slot connection, said connection leaving a passage between said tool and said support, and means directing the exhaust motive fluid of the tool into said passage.

2. The combination with a fluid pressure tool of a support therefor, a tang on said support, spaced flanges on said tool forming a slot in which said tang is received, means securing said flanges to said tang, said tang being of insufficient length to fill said slot thereby providing a passage, and means di-

recting the exhaust motive fluid of said tool into said passage.

3. The combination with a fluid pressure percussive tool, of a casing in which said tool is slidably mounted, means discharging the exhaust motive fluid of said tool within said casing, a support providing a flat member or tang, means securing said casing to said member comprising a flange clamped in face engagement with said member, said casing having an exhaust opening directed toward said flange, and said tang being spaced from said casing at said opening and cooperating with said flange to provide an exhaust deflecting passage in communication with said exhaust opening.

4. A support having a base, a hollow post adjustable thereon, arms adjustably mounted on said post, a fluid pressure tool mounted upon one of said arms, motive fluid supply means for said tool including a throttle valve, means on said tool carrying arm for supporting said valve above and in spaced relation to said post, a pedal lever mounted on said base for actuating said valve, a connection between said lever and said valve extending through the bore of said post, and manually operable means for adjusting the length of said connection and for locking it against change when adjusted.

5. A pedestal support for a power tool comprising a base, a hollow post adjustably secured upon said base, means carried by said post for supporting a power tool, a throttle valve for the tool in axial alignment with said post, a treadle mounted on said base, adjustable connecting means for operating said valve extending through the bore of said post between said treadle and said throttle valve comprising rods having a screw-threaded connection with each other, a clevis for securing the lower one of said rods to said treadle and adapted to prevent the lower rod from rotating with respect to the base, a valve stem for the throttle valve disposed in axial alignment with the upper rod, a slideable connection between the upper rod and the valve for permitting limited reciprocating movement and manually releasable means for securing the upper rod to the valve to prevent turning.

Signed by us at Detroit, in the county of Wayne and State of Michigan, this 29th day of May, 1928.

EDWARD W. STEVENS.
DONALD A. YOUNG.
